CLAIM

The ornamental design for door handles for switchgear cabinet, as shown and described.

DESCRIPTION

FIG. 1 is a front perspective view of a first embodiment of a door handles for switchgear cabinet;

FIG. 2 is a front view;

FIG. 3 is a rear view;

FIG. 4 is a left side view;

FIG. 5 is a right side view;

FIG. 6 is a top view;

FIG. 7 is a bottom view;

FIG. 8 is a front perspective view of a second embodiment of a door handles for switchgear cabinet;

FIG. 9 is a front view;

FIG. 10 is a rear view;

FIG. 11 is a left side view;

FIG. 12 is a right side view;

FIG. 13 is a top view; and,

FIG. 14 is a bottom view.
